UNITED STATES PATENT OFFICE.

OREST PUSINO, OF HELSINGFORS, FINLAND.

TYPESETTING MACHINE.

Application filed December 22, 1921. Serial No. 524,068.

To all whom it may concern:

Be it known that I, OREST PUSINO, a citizen of Russia, residing at 14 Rosavillagatan, Helsingfors, Finland, have invented 5 certain new and useful Improvements in Typesetting Machines, of which the following is a specification.

This invention relates to an improvement in type composing machines using type provided with a longitudinal slot and the object of the invention is to enable the improved type to be rapidly set up in the simplest possible way by means of the special form of slot and with comparatively 15 cheap apparatus.

The drawing illustrates the invention.

Figure 1 shows on an enlarged scale one of the new book printing type with a new form of slot in three different views.

Fig. 2 shows, diagrammatically and on a greatly reduced scale, the new apparatus in side elevation with which a type composing machine is provided to enable these new printing type to be used.

Fig. 3 shows the same in plan.

Fig. 4 shows, on an enlarged scale, a type case in three different views—a side view and two projected end views.

Fig. 5 shows diagrammatically and on a reduced scale a portion of the apparatus having two collecting rules for the type; and

Fig. 6 is a similar view looking at right angles to Figure 5.

As is shown in Figure 1, the printing type shown differ from those hitherto employed in the slot being of rectangular form and thereby forming on the type limbs of equal thickness longitudinally of the whole of the 40 longitudinal slot.

In the method of using the improved type, after each line has been composed by means of apparatus which will be herein-after described, the entire space between the 45 limbs that is to say the width of the slot is completely filled up by metal rules. Only when this condition is fulfilled that is to say when the width of the slots in the line is filled up is printing made possible. In the opposite case the letters when pressed into columns of type raise themselves and the ends of the limbs will bend or break off. For this reason the rectangular form of the 50 slot that is to say the slot with parallel sides is the only one which affords the possibility

of enabling the slots to be filled up by metal rules.

The method of composing the above type is carried out in the following way and by means of the following apparatus.

A machine for carrying out the above mentioned method is hereinafter described.

For each letter or for each printing character there is provided in the type composing machine a guide or rule 3 set on the narrow edge, inclined to the horizontal, and on which all the type of the same kind are mounted. The thickness of this rule is somewhat less than the width of the incision in the foot of the type, so that the latter 70 can slide along the rule by reason of their own weight. On a rule of this kind are mounted for example all the type bearing a small "a" and on a second rule all the type bearing a small "b," and so on in the 75 quantity necessary for use, for example 500 of each. These type are held back from sliding down the rule by a lug 4 on the upper edge of the rule and by a pin 5 passed through the rule further down. When the 80 corresponding key of the type composing machine is struck the foremost type is raised by the levers corresponding to this key to such a height that neither the above mentioned lug 4 nor the above mentioned 85 pin 5 prevents this type from sliding down, and it therefore slides downwards along the lower part of the rule, while all the succeeding type move forwards by the thickness of one type. The mechanism necessary 90 for this purpose consists of a block 6, controlled positively in a vertical direction and which is raised by the aid of the lever 7, the connecting rod 7^I, the bell crank lever 7^{II}, the connecting rod 7^{III} and the key lever 95 7^{IV}. 7^V is in this case the fixed pivot point. After the key has been struck the tension spring 7^{VI} brings the key back again into the original position.

To the lower end of the rule 3 is attached 100 a rectangular tube 8 the internal diameter of which is somewhat greater than the cross section of the particular type, so that the latter can fall into it. The upper part of the wall of this tube next to the rule 3 105 is cut away, so that the type may slide along the rule into the tube. The lower part of this tube 8 is turned through an angle around the axis of the tube, and this angle of rotation is equal to the angle be- 110

tween the rule 3 and the collecting rule 9. Being controlled by the walls of the tube 8 the type as it falls is likewise rotated about its vertical longitudinal axis and seats itself on the collecting rule 9 placed below the tube. As this rule is also inclined towards the horizontal, the type slide down along it, until they come in contact with a stop 10 at the end of the collecting rule 9. Instead of the helically twisted tube 8 other appliances may also be used for transferring the type from the rule 3 to the collecting rule 9.

For each separate letter or for each separate character there is a key with its corresponding lifting mechanism and rule 3 in the type composing machine. Each rule is charged with the type indicated on the corresponding key and every time a key is struck the corresponding type slides down on to its rule and the type collect in the desired succession on the collecting rule 9. When a line has been composed, the compositor removes the stop from the rule 9 and pushes all the type of the entire line on to a line rule 11. For this purpose the line rule 11 is firmly clamped in a straight line to the rule 9 at the end thereof. The thickness of the rule 11 is exactly equal to the width of the incision 1 in the type so that the rule completely fills up this incision. At the right hand or more remote end of the rule 11 is mounted a stop 12, which suitably limits any greater movement of the type than the length of a line. After the letters have been moved from the collecting rule to the line rule the stop 10 is returned to its former position, the line rule with the composed line of type is removed and a fresh line rule 11 clamped in the holder provided therefor.

This method of clamping the type by the aid of a rule which fills up the entire width of the slot in the type enables further operations with the composed lines to be carried out that is to say the lines can be more firmly clamped together and prints obtained therefrom. Any one letter can however be removed from the line for the purpose of making say necessary corrections, and the desired one inserted in its place, while the other letters in the line do not fall apart as they are held in place by the metal rules pushed into their slots. After they have been printed from the letters are taken apart or melted down and used again in a machine for the manufacture of new type.

Instead of inclined rules down which the type slide into the magazines horizontal rules may also be used, but in such case they must of course be provided with appliances for pushing the type along them.

In order to conveniently supply the machine with fresh type the upper end of the rule or knife 3 may be made interchangeable.

Such rules are enclosed in a rectangular tube and form a type case, as shown in Figure 4. In this figure the rules themselves are denoted by 15 while 13 is a metal tube or a cover which tube or cover is intended to support the rule and also to keep in the type. Two wire forks 14 prevent the type from falling out of the chambers.

Prior to the filling of the cases one of the forks 14 is removed and again replaced when the cases have been filled. The type are mounted in these cases in position ready for use i. e. the same kind of type in each chamber. When in use the cases are fixed in the machine and in such a way that one of the rules 15 lies in a straight line with the rule 3 and the ends of these rules which are next to each other placed close against each other, the fork 14 again withdrawn and the type run into the machine, i. e. they move down to the nose of the rule 3.

The single collecting rule 9, on account of the great number of characters used in printing, will be of considerable length which may cause some inconvenience in the operation of the machine. In order to obviate this disadvantage the collecting rule 9 may be made in two parts, as shown in Figures 5 and 6 at 16 and 16¹.

One half of the magazine rules 3 is connected to the collecting rule 16 and the other half to the collecting rule 16¹. The keys, which correspond to the first half of the letters, are connected to the lever plates 17, and those which correspond to the other half to the lever plates 17¹. The type on both the collecting rules 16 and 16¹, are transferred in the operation of composing to a common collecting rule 18. This collecting rule 18 is intended to lie in line with the collecting rule 16 when one of the keys of the first group is struck and in line with the collecting rule 16¹ when the key that is struck belongs to the second group. The mechanism which produces this movement of the collecting rule 18 will be described hereinafter.

At both ends of the rows of levers 17 and 17¹ two levers 19 and 19¹ are pivotally mounted on a common axis. The levers 19, and 19¹, are connected to each other by rods 20 and 20¹. On the depression of a key one of the rods 20 with the levers 19 is rotated through a certain angle by one of the moving levers 17. Each of the levers 19 and 19¹ is connected by rods 21 and 21¹ to the levers 22 and 22¹. On the same levers are pivotally mounted pawls 23 and 23¹. In the extreme rearward position of the lever 22 these pawls are held out of engagement with the recesses 25 and 25¹ in the wheel 26 by the aid of pins 24 and 24¹. On the depression of a key one of the levers 22, with the pawl 23, is pushed forward and the pawl, controlled by the pin 24, is

brought into engagement with the recess 25, and the wheel 26 consequently rotates on its axis. The fixed pin 24 works in a curved slot cut out in the rearward part of the pawl 23. On the release of the key the levers 19 and 19¹ are returned to their original position by springs 28 and 28¹.

On the end of the shaft 27 is mounted a lever 29, which is connected by the aid 10 of a rod 30 to the lower edge of the collecting rule 18. This collecting rule has a parallel movement, which is permitted by two joints 31 which are pivotally attached at 32. When the wheel 26 is rotated the 15 rod 30 moves the collecting rule 18 towards one or other of the collecting rules 16 and 16¹. When the joints 31 have been guided over their dead points, the collecting rule is pushed towards one of the adjusting 20 screws 33 by the spring 34 which are arranged under the collecting rule in the middle position.

The rod 35, which connects the second arms of the bell crank levers 31 to each 25 other, serves to ensure the parallel movement of the collecting rule 18.

What I claim and desire to secure by Letters Patent of the United States is:—

1. Apparatus for composing printing 30 type having longitudinal parallel slots of rectangular cross section comprising a series of rules serving as magazines for the type, lugs formed on the edges of the rules for retaining the type thereon; means for liberating the type one by one in the required order and means for transferring the liberated type to a common collecting rule.

2. Apparatus for composing printing 40 type having longitudinal parallel slots of rectangular cross section comprising a series of magazine rules, a lug on each of said magazine rules to retain the type thereon, means for raising the first of the type on any one of the magazine rules in order that 45 it may be separated from the remaining type and pass over the said lug, and means for collecting the type so liberated on a common collecting rule.

3. Apparatus for composing printing type 50 having longitudinal parallel slots of rectangular cross section comprising a series of magazine rules, a lug on each of said maga-

zine rules to retain the type thereon, means for raising the first of the type on any one of the magazine rules in order that it may be 55 separated from the remaining type and pass over said lugs, and helically twisted tubes arranged to transfer the type liberated from the magazine rules to a common collecting rule.

4. Apparatus for composing printing type having longitudinal parallel slots of rectangular cross section comprising a series of rules serving as magazines for the type, means for liberating the type one by one in 60 the required order, means for transferring the liberated type to a common collecting rule and means for transferring the type from said common collecting rule to a line rule.

5. Apparatus for composing printing type having longitudinal parallel slots of rectangular cross section comprising a series of magazine rules, a lug on each of said magazine rules to retain the type there- 75 in, means for raising the first of the type on any one of the magazine rules in order that it may be separated from the remaining type and pass over said lug, and means for collecting the type so liberated on a common 80 collecting rule, means being provided whereby the type may be finally transferred from a collecting rule to a line rule, said line rule completely filling the width of the slots in the type.

6. Apparatus for composing printing type having longitudinal slots of rectangular cross section comprising a series of magazine rules, means for liberating the type one by one in the required order, means for trans- 85 ferring the liberated type to a common collecting rule and means provided for replenishing the type on said magazine rules consisting of chambers having rules located therein to support the type adapted to be 90 connected to the magazine rules in order that the type in said chambers may be transferred to said magazine rules.

In testimony whereof, I affix my signature in presence of two witnesses.

OREST PUSINO.
